UNITED STATES PATENT OFFICE.

WILLIAM DALTON, OF SCHENECTADY, NEW YORK.

PROJECTILE-FUSE.

1,208,105.

Specification of Letters Patent. Patented Dec. 12, 1916.

Application filed July 18, 1916. Serial No. 109,887.

To all whom it may concern:

Be it known that I, WILLIAM DALTON, of Schenectady, in the county of Schenectady and State of New York, have invented a certain new and useful Improvement in Projectile-Fuses, of which improvement the following is a specification.

My invention more particularly relates to explosive projectile fuses, in the operation of which a percussion element is caused to fire an explosive charge when the velocity of the projectile, while in flight, is retarded by any obstacle.

The objects of my invention are to provide a flash port in a percussion element, in order to avoid the cost of drilling a long port in the fuse body; to provide a simpler and more effective safety percussion element, which will guard against the accidental firing of the explosive charge, during the loading and transportation of the projectile; to provide a simpler form of fuse body, by eliminating a long tortuous port, in order to avoid losses from imperfect workmanship and porosity of the material; to provide means for positively arming the percussion element at the instant it starts upon its flight, by the inertia of a reciprocating member; and to provide a centrifugally actuated member adapted to coöperate with the inertia member, for the purpose of positively arming and holding the percussion element in its armed position during flight, and for automatically disarming the percussion element when the projectile rotates at less than a predetermined speed.

The improvement claimed is hereinafter fully set forth.

In the accompanying drawings: Figure 1 is an axial section through a well known type of projectile fuse, illustrating an embodiment of my invention; Fig. 2, a partial section, illustrating the armed position of my improved percussion element, at the instant the projectile is fired from the gun; Fig. 3, a section illustrating the firing position of the percussion element, at the instant the projectile is retarded when in flight; Fig. 4, a detail plan of the percussion element, partly in section; and, Fig. 5, an axial section, illustrating a modification of structural detail.

In the practice of my invention, referring descriptively to the specific embodiment thereof which is herein exemplified, the body, 1, of the fuse, carries the powder timing train rings, 2 and 3, which are fastened to the body by a closing cap, 4, in the usual manner. A concussion element, 5, which is inclosed by the cap, is adapted to fire the powder trains, 2^a and 3^a, at the instant the projectile starts from a gun. The base powder charge in the chamber, 6, is fired by the timing powder trains, as usual, at the instant corresponding to the adjusted setting of the timing train ring, 3, if it has not been previously fired by the action of my improved percussion element to be hereinafter described. A closing screw, 8, provided with wrench sockets, 8^a, is screwed against a seat, 1^b, on the body, to tightly close a centrally disposed percussion chamber, 1^a, and the annular base charge powder chamber, 6, in the usual manner. As shown in Figs. 1, 2, 3, and 4, the percussion spool, 7, the bore of which is adapted to contain a powder core, 7^c, is centrally disposed within the chamber, 1^a, and is supported and guided at its back end by the side walls of the chamber, 1^a, and at its front end by the reciprocating inertia arming sleeve, 9, and by the walls of the reduced front section of the percussion chamber, forming a firing cavity, 1^m, so as to permit it to slide toward and from a firing pin, 14, which projects inwardly from the front end of the reduced chamber section forming the firing cavity.

The annular seat, 8^b, against which the spool, 7, abuts, is of ample size to resist crushing when suddenly accelerating and impelling the spool, at the instant the fuse is fired from a gun. A washer, 8^d, and a fiber disk, 8^e, form a partition between the charge of powder, 8^f, in the closing screw, 8, and the spool, 7, a small intervening space being interposed, as illustrated. A disk, 8^g, closes the outer or back side of the screw, in the usual manner. The ports, 8^h, are of the usual form, and establish communication between the powder in the closing screw and the annular chamber, 6. The slotted reciprocating arming inertia sleeve, 9, which is slidingly fitted in and guided by the per-

sion chamber wall; bears forwardly against and positions the inwardly projecting arms, 10^a, formed on the front extremities of one or more centrifugal triggers, 10. These triggers abut against the annular seat, 1^a, and are loosely embraced by the slots, 9^b, formed in the sleeve, and are in sliding contact therewith, so as to be unlocked thereby from engagement with the spool, by the inertness of the arming sleeve, as the projectile starts forward in its flight. A helical spring, 12, abuts against the inertia arming sleeve, and against a flange, 7^a, formed on the back end of the percussion spool, 7. The flange, 7^a, also provides seats, 7^b, for the back or abutting ends of the triggers, when the percussion element is in its normally locked or disarmed position, as shown in Fig. 1. The trigger seats, 7^b, are adapted to abut against the rear ends of the triggers, and thereby to lock the spool when abutting against the closing screw, 6, and when in its normal safely locked and disarmed position. The slots, 9^b, formed in the reciprocating arming sleeve, 9, are made of such width, measured laterally, that when the sleeve is positioned at the instant of firing the gun, as shown in Fig. 2, the triggers are caused to move outwardly, from their inwardly inclined locking positions, shown in Fig. 1, to their vertical unlocked and armed positions against the percussion chamber as shown in Fig. 2. When in this position, the spring, 12, is completely compressed, and inclosed by an annular spring housing, 9^c, formed in the arming sleeve. This position is only temporarily held by the sleeve and the spring, as they are being rapidly accelerated during the brief time which elapses while leaving the gun, and until the spring resilience overcomes the inertia of the sleeve and equilibrium is again established between the forces governing the movement of the several parts forming the percussion element, at which time the sleeve is pushed forward by the spring, against the arms, 10^a. Further movement thereof is opposed and prevented by centrifugal force generated in the triggers when the fuse is rotated at or above a predetermined arming speed. This novel and important feature of the percussion element provides a positive means of unlocking and arming the several triggers simultaneously, at the instant the gun is fired, and thereby prevents any possibility of firing failures from inoperation of an imperfect trigger. Furthermore, the centrifugal force due to the rotative speed of the fuse and triggers, holds the percussion element in its armed position until the speed drops below the predetermined arming speed, after which the several parts of the percussion element automatically return to their normal safely locked and disarmed position shown in Fig. 1. This novel con-

struction thereby prevents explosions which are frequently caused in the operation of prior devices which remain dangerously armed after the projectile is once rotated above its arming speed. Such danger is, unfortunately, increased for the reason that the exterior appearance of a fuse does not indicate the fact that it has been accidentally armed, as, for example, when unintentionally rolled down an incline, after which the projectile would explode if dropped endwise a very short distance. The inertia arming sleeve also guides and centrally positions the spool, 7, and a threaded cup nut, 13, which is screwed upon the front end of the spool, 7, for the purpose of fastening a percussion detonator cap, 13^a, in such manner as to fairly strike the firing pin, 14, when the percussion spool, 7, moves forward to its firing position shown in Fig. 2. The cap fires the powder core, 7^c, and thereby ruptures the fiber disk, 7^d, which closes the back end of the spool. The fire-flash continues rearwardly, ruptures the disk, 8^e, and fires the base charge, 8^f, and the charge contained in the chamber, 6, and, with this added force, fires an explosive charge in the projectile, which is not shown, as it may be of any of the known constructions.

The compressive force of the spring, 12, is so proportioned and transmitted to the centrifugal triggers, 10, by the inertia arming sleeve, 9, and the projecting arms, 10^a, as to provide a predetermined centripetal force. This force only permits an outward unlocking movement of the back ends of the triggers, which will clear the seats, 7^b, and thereby arm the percussion element, at rotative speeds of the projectile above 2000 revolutions per minute, or such other predetermined speed of rotation, as may be desired.

As illustrated in Fig. 1, in the practice of my invention, the percussion element is assembled in the chamber, 1^a, in its normally locked and disarmed position. It comprises the percussion spool, 7, with the detonator cap, 13^a, fastened thereto by the cup nut, 13; and the triggers, 10, which are embraced by the slotted arming sleeve, 9. These triggers are held in their inner disarmed positions by spring pressure, which is transmitted to them, from the spring, 12, through the arms, 10^a, and the arming sleeve, 9. The spring, 12, also normally positions the spool, with its attached parts, against the closing screw, 8, at a safe distance from the firing pin, 14, so as to permit the back ends of the inwardly inclined and longitudinally disposed triggers to abut against the seats, 7^b, and thereby lock the spool in the normal disarmed position shown.

The mass and form of the centrifugal triggers are so proportioned, relatively to the centripetal force due to the compressive

resilience of the spring, as to require, during the flight of a projectile, a fuse arming rotative speed of approximately two thousand revolutions per minute, to arm the element by the centrifugal force developed thereby in the triggers. This force throws them outward, clear of the flange, and into the armed position of the element. This position is normally occupied during flight, up to the instant the projectile meets a retarding obstruction. The instant it is retarded, the spool and its attached parts instantly fly to the firing position shown in Fig. 3, strike the pin, 14, and fire the explosive charge, as already described.

When inserting the projectile in a gun, the percussion element is normally positioned, as shown in Fig. 1. The instant it starts on its flight from the gun, the inertia of the arming sleeve, 9, causes the related parts to move relatively forward, and the centrifugal triggers are thereby forced outward from locked engagement with the spool, 7, into armed position before coming to a brief rest against the flange, 7^a. The spool meanwhile more firmly seats itself against the closing screw because of its own inertia. When the projectile has acquired its maximum velocity of flight, and equilibrium is established in the impelling forces acting on the several related parts forming the percussion element, the spring slides the sleeve, 9, forward against the trigger arms. At the instant the projectile is retarded in its flight, the spool suddenly slides forward, firing the detonator cap against the firing pin and exploding a projectile powder charge, providing it has not been previously fired by the timing powder trains, 2^a and 3^a. The leverage due to the relative difference in lengths between the centrifugal triggers, 10, and their arms, 10^a, offers sufficient resistance and lapse of time, required by the corresponding movement of the sleeve, 9, to overcome the centrifugal trigger resistance, and permit the spool to clear the triggers before it is again locked thereby.

When applying the improvement in a well known type of fuse shown in Fig. 5, wherein the detonator cap is fixed in the front end of the chamber, the firing pin, 14, is carried by the reciprocating member, here indicated by 7^x, and the spring, 12, is located outside of the triggers and adjoining the wall of the chamber. The operation of the mechanism is similar to that of the construction first described.

If, by accident, during transportation or otherwise, the fuse is rotated at a sufficiently high speed to arm the percussion element, the compressive force of the spring will automatically return the several parts forming the element, into their locked and disarmed position immediately after the rotation falls below a predetermined arming

speed. This is an important and valuable feature which avoids the great danger from handling an armed fuse or explosive projectile after it has accidentally been rolled down an incline or otherwise rotated above the arming speed.

I claim as my invention and desire to secure my Letters Patent:

1. The combination, in an explosive projectile fuse, of a percussion chamber; a firing pin and a detonator cap oppositely disposed therein; a reciprocating member adapted to explode the cap against the firing pin; means for transmitting fire flash from the cap to a powder charge; one or more centrifugal triggers engaging and normally locking the reciprocating member in disarmed position; means for pivotally supporting and guiding the triggers; a movable inertia member adapted to unlock the triggers and arm the reciprocating member when the fuse begins its flight; and automatic means opposing the motion of the reciprocating member, the inertia member, and the triggers, for normally holding the reciprocating member in locked disarmed position, releasing it after beginning flight, and again locking it at a rotative speed of the fuse below a predetermined arming speed.

2. The combination, in an explosive projectile fuse, of a percussion chamber; a firing pin and a detonator cap oppositely disposed therein; a reciprocating member adapted to explode the cap against the firing pin; means for transmitting fire flash from the cap to a powder charge; one or more centrifugal triggers engaging and normally locking the reciprocating member in disarmed position; means for pivotally supporting and guiding the triggers; laterally projecting arms formed on the triggers; a movable inertia sleeve encircling the reciprocating member, so as to normally bear against said arms, and to slidily bear against the triggers and unlock the reciprocating member when the fuse begins its flight and the sleeve is thereby given a rearward motion away from the arms; and a spring opposing the motion of the reciprocating member, the inertia sleeve, and the triggers, and normally holding the latter in locked engagement with the reciprocating member, in disarmed position and releasing them after beginning flight.

3. The combination, in an explosive projectile fuse, of a percussion element; a firing pin and a detonator cap oppositely disposed therein; a reciprocating member adapted to explode the cap against the firing pin; means for transmitting fire flash from the cap to a powder charge; one or more centrifugal triggers engaging and normally locking the reciprocating member in disarmed position; laterally projecting arms formed

on the triggers; a movable inertia member bearing on the arms and adapted to unlock the triggers; slots formed in the inertia member, embracing and positioning the front ends of the triggers; and a spring opposing the motion of the inertia and reciprocating members, normally holding the triggers in said disarmed locked engagement with the reciprocating member, and releasing them after beginning flight.

4. The combination, in an explosive projectile fuse, of a percussion chamber; a firing pin and a detonator cap oppositely disposed therein; a reciprocating member adapted to explode the cap against the firing pin; means for transmitting fire flash from the cap to a powder charge; one or more centrifugal triggers engaging and normally locking the reciprocating member in disarmed position; laterally projecting arms formed on the triggers; a movable inertia member bearing on the arms and adapted to unlock the triggers; slots formed in the inertia member, embracing and positioning the front ends of the triggers; a slotted flange formed on the reciprocating member and oppositely disposed to the inertia member and embracing and positioning the rear ends of the triggers; trigger seats formed on the reciprocating member normally engaging the triggers; and a spring interposed between the inertia member and slotted flange, for normally holding the reciprocating member in locked disarmed position and releasing it after beginning flight.

5. The combination, in an explosive projectile fuse, of a percussion chamber; a firing pin and a detonator cap oppositely disposed therein; a reciprocating member adapted to explode the cap against the firing pin; a guiding flange formed on the rear end thereof; means for transmitting fire flash from the cap to a powder charge; one or more centrifugal triggers engaging and normally locking the reciprocating member in disarmed position; an inertia sleeve encircling the reciprocating member, so as to slide toward the guiding flange and unlock the triggers after beginning flight; and a spring interposed between the inertia sleeve and the reciprocating member, to hold them in normal disarmed position until beginning flight.

6. The combination, in an explosive projectile fuse, of a percussion chamber; a seat formed in the front end thereof; a firing cavity encircled by the seat; a firing pin and detonator disposed therein; a reciprocating member disposed within the chamber at the rear of the firing cavity and against the rear end of the chamber, and adapted to explode the cap against the firing pin; a guiding flange formed on the rear end thereof; one or more centrifugal triggers engaging and normally locking the reciprocating member in disarmed position; an inertia sleeve en-

circling the reciprocating member and unlocking the triggers when sliding rearward after beginning flight; and a spring interposed between the guiding flange and the inertia sleeve, and normally holding the sleeve against said seat, and holding the reciprocating member against the rear end of the chamber, in its locked disarmed position, until after beginning flight.

7. The combination, in an explosive projectile fuse, of a percussion chamber; a firing pin and a detonator cap oppositely disposed therein; a reciprocating member adapted to explode the cap against the firing pin; means for transmitting fire flash from the cap to a powder charge; one or more centrifugal triggers engaging and normally locking the reciprocating member in disarmed position; means for pivotally supporting and guiding the triggers; a movable inertia member adapted to unlock the triggers and arm the reciprocating member when the fuse begins its flight; an annular spring housing and seat formed on the inertia member; and a spring disposed in the housing opposing the triggers, the reciprocating, and the inertia members, and normally holding the reciprocating member in locked disarmed position until released and armed by the inertia member after beginning flight.

8. The combination, in an explosive projectile fuse, of a percussion chamber; a firing pin fixed in the front end thereof; a percussion spool disposed within the chamber and adapted to slide toward and from the firing pin; a detonator cap carried in the front end of the spool; means for transmitting a fire flash therefrom to a powder charge; one or more centrifugal triggers normally engaging and locking the spool in disarmed position; means for pivotally supporting and guiding the triggers; a movable inertia sleeve, guided by the chamber and encircling and guiding the detonator cap into contact with the firing pin; and means opposing the motion of the spool, the sleeve, and the triggers, and normally holding the spool in locked disarmed position, until released and armed by the inertia member at the beginning of flight.

9. The combination, in an explosive projectile fuse, of a percussion chamber; a firing pin and a detonator cap oppositely disposed therein; an axially disposed longitudinally reciprocating member adapted to explode the cap against the firing pin; trigger seats formed on the rear end thereof; trigger seats formed in the front end of the chamber; means for guiding the reciprocating member; one or more inwardly inclined and longitudinally disposed centrifugal triggers normally interposed between said seats and locking the reciprocating member; an inertia arming sleeve interposed between said reciprocating member and the triggers and

in sliding contact therewith, so as to unlock the triggers and arm the reciprocating member when the projectile begins its flight; and means opposing the motion of the reciprocating member, the inertia sleeve, and the triggers, and normally holding the reciprocating member in disarmed locked position

until released and armed by the inertia member at the beginning of flight.

WILLIAM DALTON.
